UNITED STATES PATENT OFFICE.

EDWARD J. HART, OF PHILADELPHIA, PENNSYLVANIA.

UNDERFEED STOKER.

Application filed October 20, 1921. Serial No. 508,982.

To all whom it may concern:

Be it known that I, EDWARD J. HART, a citizen of the United States, residing at Philadelphia, in the county of Philadelphia and State of Pennsylvania, have invented new and useful Improvements in Underfeed Stokers, of which the following is a specification.

My invention relates to a new and useful improvement in underfeed stokers, and is a continuation in part of my co-pending application, Serial Number 370,651, dated April 2nd, 1920, and primarily has for its object to so feed the fuel to the fire bed as to bring about a complete distribution of the fuel and to produce a high efficiency in the combustion thereof, this result being accomplished by providing a main retort beneath the fire bed, branch or secondary retorts leading from the main retort, and means for feeding the fuel to the main retort, and also means for feeding fuel from the main retort to the secondary retorts and from the latter to the fire bed.

A further object of my invention is to provide reciprocating grate bars so constructed and arranged as to give the fuel of the fire bed a gradual movement outward from the main conduit.

A still further object of my invention is to provide a three-zone air system for properly feeding the air under different pressures to the different zones of the fire bed.

With these and other ends in view, this invention consists in the details of construction and combination of elements herein-after set forth and then specifically designated by the claims.

In order that those skilled in the art to which this invention appertains, may understand how to make and use the same, I will describe its construction in detail, referring by numerals to the accompanying drawings forming a part of this application, in which:

Fig. 1, is a front elevation of a boiler or like furnace showing the operating mechanism of my improved stoker.

Fig. 2, is a plan view of a part of the interior of a furnace equipped with my improved stoker and illustrating the relation of the hopper and feeding mechanism thereto, said hopper and mechanism being on the exterior of the furnace.

Fig. 3, is a section at the line 3—3 of Fig. 2.

Fig. 4, is a section at the line 4—4 of Fig. 2.

Fig. 5, is a section at the line 5—5 of Fig. 2.

Fig. 6, is a detail plan view of the operating mechanism for the ash shelves.

Fig. 7, is a section at the line 7—7 of Fig. 6.

Fig. 8, is a central longitudinal section of one of the grates.

Fig. 9, is a side elevation of one of the grates.

Fig. 10 is an end view of the plunger and its connected pusher rod.

Fig. 11 is a side elevation thereof with a part of the pusher rod broken away.

In carrying out my invention as here embodied, 1 represents the furnace, the walls of which may be of any suitable construction, and within this furnace is located a main retort 2 here shown as extending through the center thereof below the level of the grate surface. From this main retort extend the secondary retorts 3 which latter may be arranged in two sets, one set on each side of the main retort and the bottoms of said secondary retorts are on a lower level than the bottom of the main retort. The secondary retorts have spaces therebetween for the positioning of the grates 4, these grates having the flanges 6 adapted to ride upon the upper edges of the retorts which are inclined as indicated at 5 so that when the grates are reciprocated outward they will have a slight upward movement for the purpose hereinafter described.

Each of the grates is constructed in the form of steps, each step having two side walls converging toward each other terminating in an apex, and in these side walls are located the draught outlets 7; also each of these grates has a hollow head 8 through which the draught openings 9 are formed, and between adjacent grates is located a hollow head 10 which corresponds to the shape of the heads of the grates, thus forming a sectional breast wall for the upper portion of the main retort 2 over which the fuel during the process of feeding flows.

The grates are given a reciprocating motion by the rock shafts 11, each of which shafts carries a series of projections 12 pro-

jecting between the lugs 13 and 14 formed upon the grates so that as these shafts are rocked each set of grates will be given a limited outward and inward movement to 5 and from the main retort.

These rock shafts extend through the front wall of the furnace and have the levers 15 secured on their outer ends, each lever carrying a stud 16 with which the slotted 10 end of one of the connecting rods 17 is adapted to engage.

18 represents the actuating bars their outer ends being fitted to slide in the bearings 19, while their inner ends are fitted to 15 slide in the bearings 20, and these bars are reciprocated by the crank wheel 21 to which 20 end of one of the connecting rods 17 is adapted to engage.

23 represents a hopper for the reception of the fuel to be fed to the furnace and beneath this hopper is located an open end cylinder 24 in which reciprocates the plunger 25, said plunger being connected by the pitman 26 with the crank 27 secured upon the upper end of the shaft 28. This shaft has 25 secured thereon a bevel gear 29 which meshes with the bevel gear 30 the latter being secured upon the main shaft 31, on which latter is also mounted the crank wheel 21. A housing 310 is provided for 30 the driving gearing and houses portions of the last mentioned shafts.

The plunger 25 carries a depending lug 32 which projects through a suitable slot formed in the open end cylinder, and to this 35 lug is adjustably attached the pusher rod 33 upon which latter are secured the pusher blocks 34 the heels of which are beveled as indicated at 35 in order to facilitate their backward movement through the fuel. By 40 the construction just described the reciprocating of the plunger 25 beneath the open bottom of the hopper 23 will feed the fuel from the hopper to the main retort and the pusher blocks 34 moving in unison with the 45 plunger 25 will assist in moving said fuel lengthwise of said retort as will be readily understood.

In order that the fuel may be fed from the main retort to the secondary or cross retorts, I provide open end cylinders or casings 36 arranged beneath the main retort the latter communicating with said cylinders through the openings 37, and within each of the cylinders 36 is fitted a plunger 55 38 adapted to slide to and fro therein, and one of the open ends of each of these cylinders communicates with one of the secondary retorts in one of the series thereof while the opposite end of said cylinder communicates 60 with one of the secondary retorts in the opposite series thereof so that when the plungers are moved to and fro the fuel flowing downward from the main retort to the cylinders 36 will be ejected from said cylinders in one direction and then the other 65

being forced into the secondary retorts. As the fuel is thus fed from the main retort to the secondary retorts it will gradually travel outward and then upward upon the inclined bottoms 3^a of the secondary retorts 3 and thus be gradually elevated to the fire bed. 70

The plungers 38 are secured upon the rods 39 which extend through suitable bearings 40 upon the secondary retorts and these rods are provided with the pins 41 with which the forked ends of the levers 42 engage, said levers being secured upon the rock shafts 43. The forward ends of the shafts 43 project through the front wall of the furnace 80 and have secured thereon the levers 44 which are connected by the notched links 45 with the actuating bars 18 by engaging with the studs 46 and 47. Thus when the actuating bar is being reciprocated as before described the plungers 38 will be moved to and fro. 85

Upon the main shaft 31 is secured a worm gear 48 with which meshes the worm 49 the latter being secured upon the drive shaft 50 adapted to receive power from any suitable source, and I prefer that the worm gear, worm and bevel gears be enclosed in a suitable oil tight casing 51 for the proper lubrication. The object of utilizing the connecting rods 17 and notched links 45 is to provide for the proper adjustment of the actuating bars 18 and the position of the levers 15 relative to said actuating bars which is readily accomplished by substituting 95 links of different lengths. 100

Beyond the outer ends of the grates 4 are located the ash shelves 52 which are secured to the shafts 53 in any suitable manner, and these shafts extend through the front wall of the furnace and have secured thereon the bevel gears 53^a which mesh with the bevel gears 54 the latter being secured upon the short shafts 56 carrying the handle bars 57 by the manipulation of which latter the ash shelves may be swung downward so as to dump the ashes therefrom into the ash pits 58. A suitable ratchet wheel 59 is fixed to each of the short shafts 56 with which coacts a pawl 59' for holding the ash shelves in their horizontal positions when set. 110

In order that air may be admitted to different zones of the fire bed under different pressures I divide the space beneath the retorts and grates into three zones, the first zone or that in which the air is under the initial pressure consisting of the main duct 60 and the space beneath the main retort 2, the second zones being represented by the spaces 61 beneath the secondary retorts and grates, while the third zones are represented by the ash pits 58. Communication between the first and second zones is controlled by the slide doors or dampers 62 115 120 125 130

while communication between the second and third zones is controlled by the hinged doors or dampers 63, each of said doors or dampers being provided with suitable means 5 for the proper manipulation thereof outside of the furnace.

The air flowing to the first zone under initial pressure will pass upward into the heads 8 and 10 and from thence through

10 the openings therein to the central portion of the fire bed or that portion of the fuel being crowded upward from the main retort 2. The air from the second zones the pressure upon which is determined by the 15 proper regulation of the dampers 62 will flow upward to the interior of the grates and thence through the openings 7 in said grates to the fire bed resting upon the grates and being fed rearward and upward from

20 the secondary retorts 3. The air from the third zones the pressure of which is determined by the proper regulation of the dampers 63 will flow upward through the ash shelves which are perforated for that 25 purpose thus supplying draught under relatively low pressure for completing the combustion of any fuel which may still remain in the ash deposited upon said shelves by the processes of feeding the fuel.

30 In my present invention the three-zone air feed is of great importance since the distribution of the fuel over the fire bed is such that the central portion thereof or that portion which is fed to the fire bed directed 35 from the main retort 2 will be relatively of considerable depth and therefore requires a relatively high pressure of air to create the proper draught therethrough, while that portion of the fuel which is fed from the 40 secondary retorts over the grates will be of less depth and therefore require less air pressure to produce the proper draught for efficient combustion and finally the unconsumed fuel which may reach the ash shelves 45 will offer less resistance to the passage of air and therefore under my system the air fed thereto is under little more than atmospheric pressure.

As it is desirable under some conditions 50 to feed a certain amount of air above the fire bed, I provide a branch duct 64 which leads from the main duct 60 to a point above the grate surface and is provided with a valve seat 65 which the valve seat 66 is 55 adapted to close, said valve being carried by a valve rod 67 which passes out through the front wall of the furnace and may terminate in a handle for the proper manipulation of the valve. By this arrangement the valve 66 60 may be opened to permit a stream of air under pressure to be projected over the fire bed or this damper may be closed to shut off the inflow of air at this point as occasion may require.

65 Suitable doors 68 are provided for access

to the space above the ash shelves to permit the stoking at these points; also suitable doors 69 are provided for access to the ash pits and likewise suitable doors 70 are provided for access to the underside of the 70 grates to remove any fuel which may fall from the grates.

While my present invention may be variously modified to adapt it to varying conditions the primary object thereof is to provide 75 for feeding the fuel to the fire through a main retort or channel and then distributing the fuel from this main retort to the fire bed through secondary or cross retorts, and I therefore do not wish to limit myself to the 80 exact details of construction as herein shown as these may be varied within the limits of the appended claims without departing from the spirit of my invention.

Having thus fully described my invention, 85 what I claim as new and useful is:—

1. In a stoker of the character described, the combination with a furnace, of a main retort located beneath the level of the fire bed, means for feeding fuel from the outside of 90 the furnace to and through said retort, secondary retorts extending laterally from the main retort in communication therewith, said secondary retorts also being located beneath the level of the fire bed, means for 95 feeding fuel from the main retort to the secondary retorts, a series of grates located between adjacent secondary retorts, and means for reciprocating said grates.

2. In a stoker of the character described, 100 the combination with a furnace, of a main retort located beneath the level of the fire bed, means for feeding fuel from the outside of the furnace to and through said retort, secondary retorts extending laterally from the main retort in communication therewith, said secondary retorts also being located beneath the level of the fire bed, means for 105 feeding fuel from the main retort to the secondary retorts, a series of grates located between adjacent secondary retorts, means for reciprocating said grates, and ash shelves located at the outer ends of the grates.

3. In an under feed stoker, a main retort located within a furnace and extending from 115 the front to the rear thereof, means for feeding fuel to said retort, two sets of secondary retorts leading from opposite sides of the main retort and extending crosswise of the furnace, and means for feeding fuel from the 120 main retort to the secondary retorts, and reciprocating grates disposed between adjacent secondary retorts.

4. In an under feed stoker, a main retort located within a furnace and extending from 125 the front to the rear thereof, means for feeding fuel to said retort, two sets of secondary retorts leading from opposite sides of the main retort and extending crosswise of the furnace, means for feeding fuel from the 130

main retort to the secondary retorts, reciprocating grates, disposed between adjacent secondary retorts, and means for feeding air to the grates in zones under a different pressure for each zone.

5. In an under feed stoker, a main retort located within a furnace and extending from the front to the rear thereof, a set of secondary retorts located upon each side of the main retort and extending crosswise of the furnace, cylinders located beneath the main retort and communicating therewith, the ends of said cylinders communicating with the secondary retorts, and a plunger located in each of the cylinders for feeding fuel from the main retort to the secondary retorts.

6. In an under feed stoker, a main retort located within a furnace and extending from the front to the rear thereof, a set of secondary retorts located upon each side of the main retort and extending crosswise of the furnace, cylinders located beneath the main retort and communicating therewith, the ends of said cylinders communicating with the secondary retorts, a plunger located in each of the cylinders for feeding fuel from the main retort to the secondary retorts, rods upon which said plungers are mounted, levers connected with said rods for reciprocating the latter, rock shafts upon which said levers are secured, and means for rocking said shaft.

7. In an under feed stoker, a main retort located within a furnace and extending from the front to the rear thereof, a set of secondary retorts located upon each side of the main retort and extending crosswise of the furnace, cylinders located beneath the main retort and communicating therewith, the ends of said cylinders communicating with the secondary retorts, a plunger located in each of the cylinders for feeding fuel from the main retort to the secondary retorts, and means for reciprocating said plunger.

8. In an under feed stoker of the character described, a main retort located within a furnace and extending from the front to the rear thereof, an open end cylinder located in alignment with the front end of said retort, a hopper mounted upon said cylinder for feeding fuel thereto, a plunger adapted to reciprocate in said cylinder for feeding fuel to the retort, a pusher rod adjustably attached to the plunger and extending lengthwise of the retort, pusher blocks carried by said rod for effecting the rearward movement of the fuel in said conduit, a crank shaft, a crank secured thereon, a pitman connecting said crank and plunger in such manner as to reciprocate the latter, a bevel gear secured upon the crank shaft, a second bevel gear meshing with the first named bevel gear, a main shaft upon which the second bevel gear is secured, a worm wheel secured upon the main shaft, a worm meshing with said worm wheel for revolving the latter from a suitable source of power, secondary retorts extending crosswise from the main retort, cylinders providing communication between the main and secondary retorts, plungers adapted to slide to and fro in said cylinders for feeding fuel from the main to the secondary retorts, rods upon which said plungers are mounted, forked levers connected with said rods for actuating the same, shafts upon which the forked levers are secured, operating levers secured upon the outer ends of the last named shaft, actuating bars, bearings in which said bars are mounted, notched links for connecting the operating levers to the actuating bars, a crank wheel carried by the main shaft, and pitmen connecting said crank wheel with the actuating rods whereby power is transmitted from the main shaft to the plungers, hollow perforated grates located between adjacent secondary retorts and adapted to ride over

secured, a worm wheel secured upon the main shaft, a worm meshing with said worm wheel for revolving the latter from a suitable source of power, secondary retorts extending crosswise from the main retort, 70 cylinders providing communication between the main and secondary retorts, plungers adapted to slide to and fro in said cylinders for feeding fuel from the main to the secondary retorts, rods upon which said plungers are mounted, forked levers connected with said rods for actuating the same, shafts upon which the forked levers are secured, operating levers secured upon the outer ends of the last named shaft, actuating bars, bearings in which said bars are mounted, notched links for connecting the operating levers to the actuating bars, a crank wheel carried by the main shaft, and pitmen connecting said crank wheel with the actuating rods whereby power is transmitted from the main shaft to the plungers. 75

9. In an under feed stoker of the character described, a main retort located within a furnace and extending from the front to the rear thereof, an open end cylinder located in alignment with the front end of said retort, a hopper mounted upon said cylinder for feeding fuel thereto, a plunger adapted to reciprocate in said cylinder for feeding fuel to the retort, a pusher rod adjustably attached to the plunger and extending lengthwise of the retort, pusher blocks carried by said rod for effecting the rearward movement of the fuel in said conduit, a crank shaft, a crank secured thereon, a pitman connecting said crank and plunger in such manner as to reciprocate the latter, a bevel gear secured upon the crank shaft, a second bevel gear meshing with the first named bevel gear, a main shaft upon which the second bevel gear is secured, a worm wheel secured upon the main shaft, a worm meshing with said worm wheel for revolving the latter from a suitable source of power, 100 secondary retorts extending crosswise from the main retort, cylinders providing communication between the main and secondary retorts, plungers adapted to slide to and fro in said cylinders for feeding fuel from the main to the secondary retorts, rods upon which said plungers are mounted, forked levers connected with said rods for actuating the same, shafts upon which the forked levers are secured, operating levers secured upon the outer ends of the last named shaft, actuating bars, bearings in which said bars are mounted, notched links for connecting the operating levers to the actuating bars, a crank wheel carried by the main shaft, pitmen connecting said crank wheel with the actuating rods whereby power is transmitted from the main shaft to the plungers, hollow perforated grates located between adjacent secondary retorts and adapted to ride over 105

the edges thereof, shafts journalled beneath the grates, projections on said shafts adapted to reciprocate said grates, operating levers secured to the outer ends of the last 5 named shafts, and notched links connecting these last named operating levers to the actuating bars whereby power is transmitted from said actuating bars to the grates.

10. In an under feed stoker, the combination with a furnace of a main retort from

which extend branch retorts and movable grates between adjacent branch retorts.

11. In an under feed stoker, the combination with a furnace, of a main retort from which extend branch retorts and reciprocating grates located between adjacent branch retorts. 15

In testimony whereof, I have hereunto affixed my signature.

EDWARD J. HART.
